ELECTRIC INITIATOR FOR FUZE

Richard H. Stresau, Washington Grove, Md., assignor to the United States of America as represented by the Secretary of the Navy

Filed May 6, 1952, Ser. No. 286,415

1 Claim. (Cl. 102—70.2)

(Granted under Title 35, U.S. Code (1952), sec. 266)

The invention described herein may be manufactured and used by or for the Government of the United States of America for governmental purposes without the payment of any royalties thereon or therefor.

This invention relates to an explosive device and more particularly to an electroresponsive detonator for use in an ordnance missile.

The present invention contemplates the provision of a new and improved low energy detonator wherein the electric initiator therefor comprises a disc composed of paper or the like having a low energy bridge wire secured thereto by means of a spray metal and in which the spray metal provides means whereby an electrical impulse is transmitted to the bridge wire from an external source of energy whereupon the bridge wire will initiate an explosive charge arranged within the detonator casing in engagement with the charge. Furthermore, the present invention provides a low energy detonator which is compact in size, efficient in operation and possesses all the qualities of ruggedness and durability during handling and transportation.

An object of the present invention is to provide a new and improved electroresponsive detonator for use in an ordnance missile.

Another object of the invention is the provision of an electroresponsive detonator having a new and improved electric initiating unit for firing an explosive charge in response to an electrical impulse received thereby.

Another object of the invention is the provision of a new and improved electrical initiating unit for a detonator having a low energy bridge wire secured thereto and fired in response to an electrical impulse received thereby for firing an explosive charge and in which means connected to an external source of electrical energy transmit the firing impulse to the bridge wire.

Still another object of the invention is the provision of an electrical initiating unit for a detonator wherein a length of fine initiating wire bonded thereto fires an explosive charge as the wire is heated to incandescence in response to an electrical impulse received thereby.

Other objects and many of the attendant advantages of this invention will be readily appreciated as the same becomes better understood by reference to the following detailed description when considered in connection with the accompanying drawing wherein:

Fig. 1 is an enlarged central longitudinal sectional view of the device of the present invention in accordance with a preferred embodiment thereof;

Fig. 2 is a cross sectional view taken on the line 2—2 of Fig. 1;

Fig. 3 is an enlarged sectional view of the initiating unit employed in the device of Fig. 1;

Fig. 4 is a view similar to Fig. 1 illustrating an alternative arrangement thereof;

Fig. 5 is a cross sectional view taken on the line 5—5 of Fig. 4; and,

Fig. 6 is an enlarged sectional view of the initiating unit employed in the device of Fig. 4.

2

Referring now to the drawing and more particularly to Fig. 1 thereof, the numeral 10 generally designates an electroresponsive detonator or primer comprising a casing 11 composed of any material suitable for the purpose such, for example, as copper or the like. Disposed within the casing 11 and secured thereto as at 12 is an inner container or supporting member 13, the inner container being spaced from the end wall 14 formed on the casing 11.

10 A sleeve 15 composed of any material suitable for the purpose such, for example, as steel or the like is arranged within the member 13, the sleeve being arranged between a flange 16 formed on one end of the member 13 and an initiating unit generally indicated by the numeral 17. The unit 17 is disposed within the member 13 in abutting engagement with the sleeve 15 and maintained in abutting engagement therewith by a flange 18 formed thereon and crimped into engagement with the unit as clearly shown on Fig. 1.

15 The initiating unit comprises a pair of discs 19 and 21 composed of any suitable insulating material such, for example, as paper, rubber or the like, the disc 19 being arranged adjacent the sleeve 15 in abutting engagement therewith, the disc 21 being arranged adjacent the flange 25 18 in abutting engagement therewith. A terminal plate 22 is arranged between the discs 19 and 21 and in abutting engagement with the disc 21. The plate 22 has formed thereon a terminal 23, the terminal being arranged in a centrally disposed opening 24 formed in the disc 21 and extending a predetermined amount therebeyond. By this arrangement an external source of electrical energy may be connected to the terminal 23.

20 A centrally disposed electrode generally indicated by the numeral 25 is secured to the disc 19 and comprises a contact member 26 formed thereon and in engagement with the plate 22. Formed on the member 26 and disposed in a centrally arranged aperture 27 formed in the disc 19 is a reduced extension or lug 28 having formed thereon a head 29 of greater diameter than the extension 28. As shown more clearly on Figs. 2 and 3 the head 29 is disposed within an elongated recess or depression 20 formed in the disc 19 and thus by this arrangement the outer surface of the head is flush with the corresponding surface of the disc 19.

25 A contact 31 is disposed within the recess 20 adjacent the head 29 and in spaced relation with respect thereto. As more clearly shown on Fig. 3 a length of fine initiating wire 32 is secured to the aforesaid elements 29 and 31 and bridges the space therebetween as at 30.

30 The elements 25 and 31 are composed of any material suitable for the purpose such, for example, as silver, silver solder, copper or the like, the aforesaid elements being applied to the opposite sides of the disc 19 in any suitable manner. The elements 26 and 29 are preferably applied by suitably masking the faces of the disc 19 and spraying thereon a molten metal whereby the elements 26 and 29 are secured to disc 19 and are integrally united as at 28. It will be understood that when the spraying operation has been completed, the free ends of the wire 60 are encased in the members 29 and 31 with the minute bridge portion 30 thereof exposed. Furthermore, the initiating wire may be composed of any metal suitable for the purpose such, for example, as tungsten or ni-chrome wire drawn and etched to a fine size in any conventional manner. By this arrangement the initiating wire is short and readily heated to incandescence in response to the momentary application of electrical energy from a suitable source.

35 Arranged within the casing 11 and disposed in engagement with the bridge portion 30 is an explosive charge 33, the charge being fired as the bridge portion of the

wire is heated to incandescence. The firing impulse to the initiating wire 32 is established from a suitable source of electrical energy by way of terminal 23, plate 22, electrode 25, through the bridge wire 32 and thence to contact 31 which is grounded to the casings by way of sleeve 15.

The detonator of Fig. 4 is similar to the device of Fig. 1 and comprises a casing 34 closed on one end as by a wall 35, the other end thereof having a flange 36 formed thereon. Disposed within the casing 34 is a cup-shaped member 37 composed of suitable insulating material such, for example, as any of the phenolic plastic materials, the member 37 being maintained within the casing 34 by the aforesaid flange 36 which is crimped into engagement with the member 37 as at 38.

A sleeve 39 composed of steel or the like is arranged within the member 37, the sleeve having a flange 41 formed thereon in engagement with the member 37. By this arrangement the sleeve is supported within the member 37.

A substantially cone shaped member 42 is arranged with the conical portion 43 of the member 37, the member 42 having formed thereon a terminal 44 disposed within a centrally disposed aperture 45 formed in the conical portion 43 and extending a predetermined amount therebeyond.

An initiating unit generally indicated by the reference character 46 is arranged between the conical member 42 and sleeve 39, the unit comprising a disc 47 composed of suitable insulating material such, for example, as heavy paper or any of the phenolic plastic materials. Secured to the disc 47 is a pair of conducting plates 48 and 49 composed of silver or the like and sprayed thereon in a molten condition, the plate 48 being in engagement with the metal sleeve 39 and the plate 49 being in engagement with the member 42. The unit is provided with a centrally disposed opening 51 extending therethrough. Arranged within the opening 51 and having the free ends 52 and 53 encased in the plates 48 and 49 respectively is an initiating element 54 composed of a length of fine wire similar to the type of wire employed with the device of Fig. 1. It will be understood that during the spraying operation the free ends 52 and 53 of the initiating wire 54 are securely encased in the plates 48 and 49 as the molten metal is sprayed onto the disc 47.

An explosive charge 55 is arranged within the casing 34 and sleeve 39, the charge also filling the opening 51 formed in the unit 46 whereupon the initiating wire is substantially in contact with and engages the charge 55. Thus in response to an electrical impulse received by the initiating wire the explosive charge 55 is fired.

If desired, an explosive charge may be initiated at a number of selected points simultaneously by employing a plurality of the detonators or primers placed along the length of the charge at predetermined spaced intervals and connected in series in such a manner as to operate in response to a momentary application of a low order of electrical energy from a suitable source such, for example, as a normally charged condenser or a voltage generating device similar to the type disclosed and claimed in the copending application of Harold J. Plumley for

Magnetic Inertia Controlled Fuze, Serial No. 535,799, filed May 16, 1944, now Patent No. 2,848,948. Furthermore, the aforesaid arrangement may be employed for firing a battery of explosive charges simultaneously by arranging a detonator in each one of the battery charges and connecting them to a suitable source of energy, it being obvious, however, that since one of the detonators is heated to incandescence by substantially 50 ergs all the detonators will be readily fired in response to a relatively low amount of energy received thereby.

From the foregoing description it will be readily apparent that a new and improved detonator and initiating unit therefor is provided wherein a fine initiating wire is secured to the surface of a disc composed of suitable insulating material, the effective length of the wire being controlled by the application of molten metal to a portion of the disc and wire and thus by reason of the minute size of the wire and the small bridge portion thereof the wire may be heated to incandescence in response to a momentary application of a very low electrical impulse received thereby, the spray metal being instrumental in providing means whereby an electrical impulse is passed through the bridge wire.

Obviously many modifications and variations of the present invention are possible in the light of the above teachings. It is therefore to be understood that within the scope of the appended claim the invention may be practiced other than as specifically described.

What is claimed as new and desired to be secured by Letters Patent in the United States is:

An electroresponsive detonator comprising a conductive casing having a flanged open end formed thereon, an explosive charge arranged within said casing, a centrally apertured base plate composed of insulating material seated upon said flanged open end, an apertured disc composed of insulating material arranged within said casing, a pair of conductive surfaces sprayed on the top face of said disc while in a molten state, one of said surfaces encompassing the aperture in said disc, a bridge wire extending between and bonded to said conductive surfaces, a conductive film sprayed on the under face of said disc while in a molten state and communicating with said one surface through said disc aperture, a conductive disc engagingly positioned between said conductive film and said base plate and having a protuberance integrally formed thereon extending through said base plate aperture, and a conductive sleeve abutting said casing and the other one of said sprayed surfaces, said casing and protuberance providing an electrical connection from said bridge wire to an external electrical energy source thereby to effect heating of said bridge wire and consequent ignition of said explosive charge.
